REBUILT SHOE LAST AND METHOD OF
MAKING THE SAME

Louis W. Reinhardt, Brockton, Mass., assignor to
George E. Belcher Company, Stoughton, Mass.,
a corporation of Massachusetts

Application November 24, 1933, Serial No. 699,570

3 Claims. (Cl. 144—309)

In the remodeling of shoe lasts or like wooden foot forms certain requirements have developed to meet current practices.

It has been the ancient practice probably since 5 the beginning of last making or that of wooden foot or hand forms, to repair or remodel by splicing, inlaying or part replacement, such portion or area as has been worn, broken or otherwise of needed repair or substitution. I do not claim 10 anything of this sort.

Modern lasts under present conditions have become an increasing item of expense to shoe manufacturers. Their potential rehabilitation value is accordingly increased.

15 Repair of remodeling or part replacement being necessary for economic reasons, I have developed certain factors which make the practical factory service for such lasts convenient and economical. Some lasts of larger size have excess 20 wood and that can be spared and can so be returned to smaller shapes. In remaking most lasts it is necessary in course of factory practice to add a new block or wedges furnishing additional material from which remodeling may be done.

25 The changes in old lasts usually desired are in the fore or toe part. The heel part and particularly the hinge area of jointed lasts, are important to save as they involve the basic cost and structural investment of the shoe manufacturer.

30 My concept is simply that of providing the best and most economical basis of re-styling or remodeling an old last to make it serve longer.

In jointed lasts it has been common practice since their advent to replace the fore part, i. e. 35 to detach the linked fore part and put on another. In single piece lasts or in others it has been old to splice, split, wedge or otherwise cabinet make the old wooden article into the new style or type or form desired.

40 My improvements and the advantages that follow will be set forth in the specification with reference to the accompanying drawings in which characteristic features are illustrated.

45 Fig. 1 indicates in side elevation a last or one of a number of lasts to be replaced or re-made and with plane of cut indicated.

Fig. 2 is a bottom view of the same with the cut indicated.

50 Fig. 3 shows such a last with the undesired toe part sawed off.

Fig. 4 shows a toe part block with indicated angular cut.

55 Fig. 5 is a face view of the angular cut of the toe block with keyhole connection formed in it.

Fig. 6 shows the old heel and joint parts united ready for turning the new toe block.

Fig. 7 shows the re-made last.

Fig. 8 a detail of my headed fastener, and

Fig. 9 shows a modified form of waist cut.

Referring to Fig. 1, I have indicated a last of 5 hinged type comprising a heel part 1, a fore part 2, and an intermediate knuckle bearing 3, and a connecting link 4 held by transverse pins 5 and heel plate 6 and the usual jack socket 7.

The broken line $x-x$ (Figs. 1 and 2) indicates a saw cut plane passing through the last at substantially the waist line. In most cases it will start on the sole near the joint between the fore and heel parts (Fig. 2). It should pass upwardly 10 and forwardly emerging somewhere at the instep forward of and below the cone.

As the waist line is that of the smallest measure 15 back of the toe portion, there will be removed by such a cut all of the larger dimensioned parts and 20 the plane of attachment beyond which the turning of the new fore part block does not have to go will be well below the new contours established by the cutters. Technically, the waist line is the 25 minimum measure around the last and is commonly determined by looping a measure about the last from the base of the instep or cone through the hollow of the arch on the sole and slipping the measure back and forth until a 30 minimum reading is obtained. The precise location of the waist line, of course, will vary according to the style of the last.

In a broader sense, I use the term "waist line" 35 to define the above described zone through which cuts can be made in accordance with my invention. The term "waist line" will, therefore, be understood to refer broadly speaking to a zone extending around the last near the base of the 40 instep and through the hollow arch on the last bottom.

In these reconstructions, the practical problem has to be met by the factory man. My concept is simple. It is that of observing the minimum 45 contour of the waist line plane. It is usually necessary to return these lasts at larger or broader contours or as is more easy, to remove some prominent excrescences as in the past high box toe or other bulging parts.

Such "freak" lasts are very easy to handle. 50 Also, it is simple to turn down an old over-size form. Such jobs do not present any problem. The trouble is to re-make a good last where the new style imposes a different shoe form or swing or spring of the fore part of such a last. This 55

usually starts, as I analyze it, at about the ball of the foot and forward toe portion.

I therefore take as a basis of my analysis that angular base line running across the forward joint 5 of the metatarsal at the forward base of the double arch. This is a sole plane of foot contact. Its over-regions are orthopedically important. I therefore, for orthopedic and more practical manufacturing reasons, place my cut as indicated 10 at the secant line through the waist.

My secant juncture plane as indicated in Fig. 1 is of minimum area as compared with other lines of cut. However, it is important as to its ability to carry stresses and strains in lasting and 15 leveling.

In carrying out my invention I cut the lasts to be re-made on their waist line plane as before described, leaving the heel part, knuckle and rear part of the fore part with its linkage intact.

20 I prepare new fore part blocks 10 of ample size to allow easy centering and turning of the new wood. For convenience, these blocks are usually first cut in oblong form and squared up carefully to permit accurate gaging and clamping. These 25 I saw at the predetermined angle of the cut off of the old last so as to obtain an exactly registering angular face but one of substantially larger area. This is of advantage in facilitating assembly as before suggested as it is not necessary as in other 30 methods to attach the new block in any exact axial alignment with the old last part. In these angular faces of the new blocks 10 I cut a key-hole slot 8 having a round entry 8¹. I first rout out the slot 8 and then go in with a flat disc cutter 35 to form the entry 8¹ then run it along the slot 8 to get an undercut as indicated in Fig. 5.

Centrally of the angular face on the remains of the old last fore part I set a headed stud 9 having a threaded shank 9¹. This can be screwed firmly 40 in the face and adjusted to just the right clearance to give a tight sliding fit in the slot 8.

When this adjustment is made the cut faces which are generally transverse of the grain are glued up and the block 10 assembled on the old 45 last parts. After the glue is set thoroughly the lasts may be centered and the new block turned to the new desired model.

In centering I take the usual heel center point half way up the back heel line and a toe center 50 such as to give the desired general posture and have plenty of wood to give the widest contours desired. By the use of blocks 10 of ample size, I avoid as before described, any necessity of fussy exact toe centering when the rest of the last is 55 in desired condition which in other methods often goes wrong and spoils the work.

Procedure may be somewhat varied. The toe 60 blocks may be of different shapes or materials than that shown. Also, the fastening may be varied although that shown is very convenient and effective and with the coacting angular faces gives a very strong joint so that the re-made lasts stand up under the heavy strains of shoe-making.

65 In posturing the assembled old last and toe

block I am able to work from a three point support at the heel plate 6 holding the back of the heel against a V-shaped rear support. This gives what is really a four point pyramidal gaging which positions the assembly while the toe center is pricked. This part of my method may also be varied, but is very simple and advantageous and combines with my concept of the large toe block. 5

The plane of severance at the waist of the last may as indicated in Fig. 9 be other than 10 on a single plane. For example, the last may be severed on its waist line by a V-shaped cut. Two erect converging kerfs are sawed in one from each side of the last at the waist line on the indicated planes Y-Y. The severed fore part is replaced 15 by a new block having a corresponding V-cut and the parts assembled and turned as previously indicated.

What I therefore claim and desire to secure 20 by Letters Patent is:—

1. As an improvement in the art of re-making used jointed lasts by the substitution of a new fore part portion, that method which consists in severing the undesirable portion of the fore part on a secant plane at substantially the waist 25 line of the old last beginning at substantially the joint line of the underinstep and extending upwardly and forwardly in advance of the cone, and in then forming a substitute fore part block having a like inclined surface, and in attaching the 30 new fore part block to the old last heel and joint portion left by the cutting with the inclined faces in abutting relation, and in turning the fore part to any desired shape to give the re-made last the desired model. 35

2. As an improvement in the art of re-making used jointed lasts by the substitution of a new fore part portion, that method which consists in severing the undesirable portion of the fore part on a secant plane at substantially the waist line 40 of the old last beginning at substantially the joint line of the underinstep and extending upwardly and forwardly in advance of the cone, and in then forming a substitute fore part block having a like inclined surface, and in mechanically interengaging the new fore part block to the old last heel and joint portion left by the cutting with the inclined faces in abutting relation, and in turning the fore part to any desired shape to give the re-made last the desired model. 45

3. A remade shoe last consisting of a used rear part having an inclined forwardly projecting face at the waist line of the last, and a new fore part having a cooperative rearwardly projecting downwardly inclined face, one of said faces having an undercut keyhole slot therein and disposed parallel to said surface, and a flat headed screw stud set in the other face and having its head parallel to its adjacent surface and slidably engaged in said slot to form a blind mechanical 55 bond, said faces being cementitiously united to hold said surfaces against relative movement on each other and unite the two last parts into a solid last. 60
